UNITED STATES PATENT OFFICE.

JOSEPH ARTHUR HENRY HATT, OF BROOKLYN, NEW YORK.

PROCESS OF MAKING PRINTING-PLATES AND PRINTING IN COLORS.

1,134,382.

Specification of Letters Patent.

Patented Apr. 6, 1915.

No Drawing.

Application filed January 14, 1913. Serial No. 742,026.

To all whom it may concern:

Be it known that I, JOSEPH ARTHUR HENRY HATT, a citizen of the United States, residing in Brooklyn, in the county of Kings and State of New York, have invented certain new and useful Improvements in Processes of Making Printing-Plates and Printing in Colors, of which the following is a specification.

10 The process relates to the art of making multi color prints and making sets of photo mechanical printing plates for printing in colors and more particularly to making such prints and sets of such plates from the same negative.

15 The invention has as one of its objects making a plurality of plates for color printing from a single negative and producing novel and useful prints and printing effects thereby; and as a further object making such plurality of plates from a single continuous tone negative; to vary and regulate at will the position and relation of screen figures to design in any particular set of 20 plates or between particular plates, without making new negatives or using a plurality of negatives; to variously dispose the screen figures for different colors to meet the particular requirements for any desired combination of colors, or particular kind of 25 prints or printing effects; to render the negative and screen figure independent of each other in color printing, and to do this with the use of a single negative in making 30 a set of color plates; to be able to make a variety of screen figures from a single negative, such as coarse line, fine line or grain, and to produce corresponding effects in color prints from a single negative; to vary 35 and arrange the screen figures in color printing to avoid disagreeable and inartistic effects, such as a moiré effect or figure in the prints; to arrange the relative position of screen figures at will, for different colors, 40 and for primary and secondary colors, and otherwise at will to meet particular requirements or particular effects desired, and a further object of the invention to effect all the foregoing in an improved and thoroughly artistic and efficacious manner.

45 These and other objects of invention will in part be obvious and in part will more fully appear hereinafter. The invention consists in the novel steps, processes and improvements herein described. The invention will 50 be found applicable in a wide field, and

among such applications it is highly useful where only a single negative is obtainable or is employed, or where all extra expense in making a plurality of color plates is to be 55 avoided, or where the color effects desired are to be created or controlled by the artist rather than to be produced by the use of color filters and a plurality of negatives from a colored original. It will be understood that these uses or applications are 60 cited by way of example and illustration and are not necessarily restrictive of the field in which the process may be used. Other objects and advantages of the invention will be set forth hereinafter in part, and in part will be apparent to those skilled 65 in the art.

In carrying out my process, by way of example, a single continuous tone photographic negative, that is, the usual negative without screen figures as distinguished from negatives made with a screen and having screen figures, is made from a suitable original such as a picture or an object or view, 70 and preferably a dry plate negative.

I make the printing plates for the various colors, respectively, directly from the photographic or continuous tone negative, referred to hereinbefore, in substantially 75 the manner set forth in my application for patent Serial No. 728,583.

I shall, therefore, in describing the preferred manner of carrying out my invention, consider same in connection with making printing plates direct from the photographic continuous tone negative by the use of a suitable screen, as for instance the screen set forth in my application for patent 80 Serial No. 728,583.

90 In making the successive printing plates from such a negative, I rotate or change the position of the screen relatively to the negative for the successive plates, whereby the grain figure upon the various plates 95 will be differently placed at proper angles, thereby in the finished color print, made by the superimposed impressions from the various plates, the various colors will be presented to the eye to be blended thereby into 100 the desired color effect, without the undesirable moiré pattern being produced.

105 The rulings or tintings of a screen are usually arranged or disposed so as to cross at right angles, and the rulings are thus ninety 110 degrees apart. If in making the second printing plate, that is, a plate for another

color, or a half tone negative therefor, the ruled screen be swung or substantially rotated through an angle of less than ninety degrees, it will be obvious that the screen pattern of the second printing plate will be correspondingly displaced or differently located in the surface of the design from the screen figures of the first plate. It will also be clear that this may be done with a third plate so that its screen figure in the design will be differently disposed or substantially rotated with respect to the screen figures of either the first or second printing plate, and so on with respect to other printing plates. In practice, however, I find it desirable with certain classes of work, such as three color work, and certain other classes, to use three different angles or positions of displacement of the rules or tinted screen, varying from each other substantially equally, that is, by one third of ninety degrees, or thirty degrees apart. However, the invention in its broader aspects is not to be regarded as being so limited. Where more than three colors are used, two or more colors which have proper harmonious relations with respect to each other may have the same displacement or screen angle, that is, have the screen figures on a printing plate similarly disposed or positioned in, and relatively to, the design, and this may be true of other groups of colors, and where it is found desirable the final design may be built up of any desired number of superimposed printings.

For certain classes of work, it will be found that certain colors may be printed with the screen or screen figures at an intermediate angle from those just described for what may conveniently be termed the main colors. By way of example, where the screens and resulting screen figures for the principal colors are substantially thirty degrees apart, as already described, certain colors such as a yellow or other very light color, or the plates for said colors, might have their screens and resulting screen figures at an angle substantially midway between those of the main colors. That is, in the example given, substantially fifteen degrees apart from the next adjacent main colors. It will be understood, of course, that the reference to angles and degrees, is not intended to be exact but rather is meant in the sense of practical manipulation in this art.

As one feature of my invention, in connection with my process, I contemplate the developing out of portions of the printing plate by the artist to secure the desired color effects. This step would correspond to the elimination secured by the use of a color filter in photo-mechanical work, although in that instance a colored original is essential. It also corresponds to the selective work of

the artist in preparing the various stones or plates for the different color printings. By manipulation in developing, however, the very nicest gradations in tone value, as well as any desired total eliminations in any part of the plate may be made, as desired by the artist. Thus any desired color effects may be obtained from any original and from a single negative thereof, expeditiously and at exceedingly low cost. In carrying out this feature of my process, the surface of the printing plate is covered with a sensitized coating such as a bichromated colloid or albumin, the negative is placed upon the surface of the plate and the screen is placed upon the negative. I preferably use a screen all parts of which are light-transmitting but the different parts varying in their degrees of light-transmitting power, having tintings of different light transmitting power, and having the parts between the tintings transparent or clear. The other plates are made in the same manner excepting that the screen is displaced or rotated, as previously described, to dispose the screen figures at a different angle. During the developing out of the plate, certain parts may be brought up or held back or eliminated at the will of the operator or artist by relatively arresting or pushing the development of the particular part of the plate, with a consequent corresponding variety or difference in result in the printing of the color upon the finished print.

The process is well adapted for the making of duo-tone plates, that is, two plates made from the same subject, and the printing of said two plates in superimposition making the picture. One plate is preferably made darker or more full in tone value than the other by a relative excess of exposure, and this plate is usually used to print the tint or lighter color. The other plate is made lighter in its tone values by a relatively minimum amount of exposure and is usually used for the darker color printing plate. When impressions from these two plates are superimposed, they produce a greater range of tone values than can be produced in one plate. Opportunity is thus also afforded, for the employment of different lines or colors on the two plates, thus giving work of great beauty and high artistic value in a simple and inexpensive manner.

In the art of three color plate making, where the cross line screen is used for the production of the plates, there is a limit of three angles that can be used and at the same time avoid the objectionable moiré pattern, thus making the difference in position of the screen figures in the three plates thirty degrees. By way of explanation of this feature of the invention, a circle comprises 360° , and if this be divided by 30° which is the

smallest angle that can be used successfully with such classes of work, we will have divided the circle into twelve angle points. Now a cross line screen necessarily has four angle points, a point at each end of the two series of lines crossing each other. It will be obvious from this that we have only three different screen positions in the entire circle, at 30° apart, or the smallest angle that can be used to avoid the moiré pattern. There are other instances, however, as in certain classes of four color work, or other numbers of colors, where the yellow or other lightest or lighter colors are placed at a point 15° away from the two other colors, that is, substantially midway between them. This is done, not because a moiré pattern is not produced but because owing to the lightness of the color it is not offensive or easily observed. With the present system of color work production, in which the cross line screen is employed, it is necessary to make each of the final half-tone negatives required, at a different angle, as regards the position of the cross line screen. For instance, one half tone negative cannot be used to produce two or more prints at two or more different angles. The main reason for this is that the screen figures and the design are combined into one negative.

With my process the negative or positive does not contain a screen figure at all, and consequently the same negative can be placed in any position as regards the screen. This is very useful in making color plates in various ways, as for instance, where one negative, which may be an ordinary photographic negative, or may be a color negative for one of the component colors of the original, is employed as the basis for making two or more colors, and it is of the greatest value when six or eight or more colors are used in the production of a color job. For instance, by way of illustration and example, the negative or positive of the blue color sensation may be used for a black at one angle; for a gray at the same angle; for a light blue at another angle, and for a dark blue at another angle. The red sensation may be used for red at one angle; for pink at another angle; and for brown at another angle.

Inasmuch as color can be successfully divided into only three color sensation by photography, it is important to be able to use the three color sensation negatives or positives to the fullest possible extent. The results may be enhanced by the use of the developable dot image process described in my application Ser. No. 728,583.

In carrying out one phase of the process of my invention, that is, the making of a duotone tripletone, or quadruple tone, where in all the various color plates are made from one negative, or positive, a suitable nega-

tive or positive is made preferably on a gelatin dry plate. This negative or positive is of the ordinary continuous tone variety.

For the purpose of easy control in the after manipulation, preferably a register mark (preferably a cross register mark) is cut in two opposite ends of the negative or positive. These register marks may also be photographed on to the negative at the time of making the exposure from the original.

A metal plate or stone is sensitized in the usual manner for either a positive or a negative, that is with either bichromated glue or bichromated albumin. The negative or positive is then placed in position at a certain definite angle, (allowing for the proper focal screen distance) on a half tone screen, and temporarily attached thereto so as to prevent movement. This may be done by pasting gum paper at the edges. The sensitized plate or stone is then placed in contact with said negative or positive and it is then exposed to a stationary or movable point of light such as an arc. This first plate, may be exposed a trifle less than the normal exposure, so that when the plate is developed it will give what may be called a light print, showing full details in the shadows. This plate is to be used to print a black or other strong color.

The negative or positive on the half tone screen is now shifted substantially either 30° or 60° in either direction and another exposure is made in a second plate. This time the exposure should be excessive so as to produce an image of a full or heavy character, an image showing full details in the high lights or lighter parts of the design or picture. This plate is to be used to print a light color, or tint, and the two plates so used to superpose their impressions over each other on one sheet of paper, would produce a duotone, without any hand work whatever.

A third plate may also be made either darker or lighter than the other two, or intermediate between them, by shifting the negative or positive another 30° or 60° .

A fourth plate may be made by making two exposures from the same angle. In fact six plates may be made by duplicating three angles. Seven and eight plates may be made by shifting the screen 15° and using this angle for one or two of the very lightest colors.

Three plates may be made on a cross line screen, and any number of plates may be made from a grain screen, all from the one negative or positive, and all superposed in printing, and at the same time avoid a moiré pattern.

The use of my developable dot invention permits a print to be made heavy or light at will.

In doing multi color work, with my invention, three negatives or positives may be made representing respectively red or magenta, yellow and blue.

5 It is also possible by the use of a combination of color filters for one exposure, that is, by exposing through one and then another filter to make a useful approximation of the negative of the black values in an 10 original.

Using either three or four negatives or positives, any number of prints can be made keeping the strong colors at angles 30° apart and using the same negatives for the lighter 15 colors at duplicate angles of the strong colors.

It will be understood that the foregoing is not restrictive of the invention but is 20 explanatory of the invention and of certain 25 of its principles, aspects and adaptations.

Other advantages and objects than those 25 specifically enumerated are realized, as will be clear to those skilled in the art, and variations may be made from the particular 30 steps described, within the scope of the appended claims, without departing from the principles of the invention. It will, of course, be understood that the term negative is intended to apply to a so-called "positive" 35 and to similar instrumentalities for impressing a design upon a light sensitive surface of a plate.

What I do claim and desire to secure by Letters Patent, is:

35 1. The process of making multi - color prints which comprises taking a single negative and making therefrom a plurality of printing plates each having a screen figure, the screen figures in one of said printing 40 plates being in different positions relatively to its design from the screen figures in another of said printing plates relatively to its design, and printing said plates in different colors in superimposition upon an impression 45 receiving material with the designs in register.

2. The process of making multi - color prints which comprises taking a single photographic negative, making a plurality of 50 printing plates from said negative by means of an instrumentality for making grain figures in the printing plate, disposing the grain figures in one printing plate in different positions relatively to the design 55 from the grain figures in another of said printing plates with respect to its design, and printing the design from said plurality of plates superimposed in register with each other, said plates being printed in different 60 colors from each other.

3. The process of making multi - color prints which comprises taking a single continuous tone negative, making a printing plate therefrom by means of a screen where-

by said printing plate will have screen figures thereon, making another printing plate from said negative by means of a screen, but changing the relative position of the screen and negative to cause the screen figures in such second plate to be in a different position relatively to the design from the screen figures on said first-mentioned plate relatively to the design on said first-mentioned plate, and printing the designs from said plurality of plates superimposed and in 75 register with each other, said plates being printed in different colors from each other.

4. The process of making multi - color prints which comprises taking a single photographic or continuous tone negative, 80 placing said negative and a figured screen in contact with each other and with one of them in contact with the sensitized surface of a printing plate, developing said plate and preparing it for printing, placing said 85 negative and said figured screen in contact with the sensitized surface of another plate, but changing the position of the screen relatively to the negative in order to change the position of the screen figures relatively to 90 the design with respect to the positions of the screen figures in the first-mentioned plate relatively to their designs, developing said plate and preparing it for printing, printing said plates in superimposition with their 95 designs in register, said plates being printed in different colors from each other.

5. The process of making multi - color prints which comprises taking a single photographic or continuous tone negative, 100 placing said negative and a figured screen in contact with each other and with said negative in contact with the sensitized surface of a printing plate, developing said plate and preparing it for printing, placing said negative and said figured screen in contact with the sensitized surface of another plate but changing the position of the screen relatively to the negative in order to change the position of the screen figures relatively to 105 the design with respect to the positions of the screen figures in the first-mentioned plate relatively to their designs, developing said plate and preparing it for printing, printing said plates in superimposition with their 110 designs in register, said plates being printed in different colors from each other.

6. The process of making multi - color prints which comprises taking a single photographic or continuous tone negative 120 and impressing said negative upon the sensitized developed surface of a printing plate by the action of light, developing said plate and eliminating portions of the design during such development, impressing said negative upon the sensitized developable surface of another printing plate by the action of light, and printing said plates in superim- 125

position with their designs in register, the plates being printed in different colors from each other.

7. The process of making multi-color prints which comprises taking a single photographic negative and impressing said negative upon the sensitized developable surface of a printing plate by the action of light, impressing screen figures on the sensitized surface of the plate together with the design from the negative, developing said plate and eliminating portions of the design during such development, impressing said negative upon the sensitized developable surface of another printing plate by the action of light, impressing screen figures on the sensitized surface of said last-mentioned printing plate but in different positions relatively to the design on said plate, and printing said plates in superimposition with their designs in register, the plates being printed in different colors from each other.

8. The process of producing multi color prints which comprises making a plurality of printing plates from the same negative by sensitizing a plurality of said plates, exposing said sensitized plates to light action through said negative and a ruled or tinted screen, displacing the screen relatively to the design for each of the plates to vary the relative position of the screen figures with respect to the design in said plates, developing said plates, and printing from said plates in superimposition in various colored inks.

9. The process of producing multi color prints which comprises making a plurality of printing plates from the same continuous tone negative by sensitizing a plurality of said plates, exposing said sensitized plates to light action through said negative and a ruled or tinted screen, displacing the screen relatively to the design for each of the plates to vary the relative position of the screen figures with respect to the design in said plates, developing said plates, and printing from said plates in superimposition in various colored inks.

10. The process of producing multi color prints which comprises making a plurality of printing plates from the same negative by sensitizing a plurality of said plates, exposing said sensitized plates to light action through said negative and a ruled or tinted screen, displacing the screen substantially angularly relatively to the negative in making the successive plates therefrom, developing said plates, and printing from said plates in superimposition in various colored inks.

11. The process of producing multi color prints which comprises making a plurality of printing plates from the same negative by sensitizing a plurality of said plates, ex-

posing said sensitized plates to light action 65 through said negative and a ruled or tinted screen, symmetrically displacing the screen relatively to the design for each of the plates to symmetrically vary the relative position of the screen figures with respect 70 to the design in said plates, developing said plates, and printing from said plates in superimposition in various colored inks.

12. The process of producing multi color prints which comprises making a plurality 75 of printing plates from the same negative by sensitizing a plurality of said plates, exposing said sensitized plates to light action through said negative and a ruled or tinted screen, symmetrically displacing the screen substantially angularly relatively to the negative in making the successive plates therefrom, developing said plates, and printing from said plates in superimposition 80 in various colored inks.

13. The process of making a set of plates for photo mechanical color printing which comprises making a plurality of printing plates from the same negative by sensitizing said plates, exposing them successively to 90 the action of light through said negative and a figured screen, displacing the screen relatively to the negative for the successive plates whereby the screen figure is correspondingly displaced relatively to the design in each of said plates, and developing said plates.

14. The process of making a set of plates for photo-mechanical color printing which comprises making a plurality of printing 100 plates from the same continuous tone negative by sensitizing said plates, exposing them successively to the action of light through said negative and a figured screen, displacing the screen relatively to the negative for the successive plates whereby the screen figure is correspondingly displaced 105 relatively to the design in each of said plates, and developing said plates.

15. The process of making a set of plates 110 for photo-mechanical color printing which comprises making a plurality of printing plates from the same negative by sensitizing said plates, exposing them successively to the action of light through said negative 115 and a figured screen, substantially symmetrically displacing the screen relatively to the negative for the successive plates whereby the screen figure is correspondingly substantially symmetrically displaced relatively 120 to the design in each of said plates, and developing said plates.

16. The process of making a set of plates for photo mechanical color printing which comprises making a plurality of printing 125 plates from the same continuous tone negative by sensitizing said plates, exposing them successively to the action of light

through said negative and a figured screen, substantially symmetrically displacing the screen relatively to the negative for the successive plates whereby the screen figure is correspondingly substantially symmetrically displaced relatively to the design in each of said plates, and developing said plates.

17. The process of making a set of plates
10 for photo-mechanical color printing which comprises making a plurality of printing plates from the same negative by sensitizing said plates, exposing them successively to the action of light through said negative and a
15 figured screen, substantially angularly displacing the screen relatively to the negative for the successive plates whereby the screen figure is correspondingly displaced relatively to the design in each of said plates, and developing said plates.

18. The process of making a set of plates for photo-mechanical color printing which comprises making a plurality of printing plates from the same negative by sensitizing said plates, exposing them successively to the action of light through said negative and a figured screen, substantially angularly and symmetrically displacing the screen relatively to the negative for the successive plates whereby the screen figure is correspondingly displaced relatively to the design in each of said plates, and developing said plates.

19. The process of making a set of plates
35 for photo mechanical color printing which comprises making a plurality of printing plates from the same continuous tone negative by sensitizing said plates, exposing them successively to the action of light through said negative and a figured screen, substantially angularly displacing the screen relatively to the negative for the successive plates whereby the screen figure is correspondingly displaced relatively to the design in each of said plates, and developing said plates.

20. The process of making a set of plates for photo mechanical color printing which comprises making a plurality of printing plates from the same continuous tone negative by sensitizing said plates, exposing them successively to the action of light through said negative and a figured screen, substantially angularly and symmetrically displacing the screen relatively to the negative for the successive plates whereby the screen figure is correspondingly displaced relatively to the design in each of said plates, and developing said plates.

21. The process of producing multi color prints which comprises making a plurality of printing plates from the same continuous tone negative by sensitizing a plurality of said plates, exposing said sensitized plates to light action through said negative and a ruled or tinted screen, displacing the screen relatively to the design in the negative for each of the plates

to light action through said negative and a 65 ruled or tinted screen, displacing the screen substantially angularly relatively to the negative in making the successive plates therefrom, developing said plates, and printing from said plates in superimposition in various colored inks. 70

22. The process of producing multi color prints which comprises making a plurality of printing plates from the same continuous tone negative by sensitizing a plurality of said plates, exposing said sensitized plates to light action 75 through said negative and a ruled or tinted screen, symmetrically displacing the screen relatively to the design for each of the plates to symmetrically vary the 80 relative position of the screen figures with respect to the design in said plates, developing said plates, and printing from said plates in superimposition in various colored inks. 85

23. The process of producing multi color prints which comprises making a plurality of printing plates from the same negative by sensitizing a plurality of said plates, exposing said sensitized plates to light action 90 through said negative and a ruled or tinted screen, displacing the screen relatively to the design in the negative for each of the plates substantially angularly and equally for the primary colors, correspondingly varying 95 the relative position of the screen figures with respect to the design in each of said plates for said primary colors, developing said plates, and printing from said plates in superimposition in correspondingly colored inks. 100

24. The process of producing multi color prints which comprises making a plurality of printing plates from the same negative by sensitizing a plurality of said plates, exposing said sensitized plates to light action 105 through said negative and a ruled or tinted screen, displacing the screen relatively to the design in the negative for each of the plates substantially angularly and equally for the primary colors, displacing said screen at an angle intermediate to those for two of the primary colors in making the plate for a secondary color, correspondingly varying the relative position of the screen figures with 110 respect to the design in each of said plates for said primary colors, developing said plates and printing from said plates in superimposition in correspondingly colored inks. 115

25. The process of producing multi color prints which comprises making a plurality of printing plates from the same negative by sensitizing a plurality of said plates, exposing said sensitized plates to light action 125 through said negative and a ruled or tinted screen, displacing the screen relatively to the design in the negative for each of the plates

substantially angularly and equally for the primary colors, displacing said screen at an angle substantially midway between those for two of the primary colors in making the plate for a secondary color, correspondingly varying the relative position of the screen figures with respect to the design in each of said plates for said primary colors, developing said plates, and printing from said plates

in superimposition in correspondingly colored inks. 16

In testimony whereof I have signed my name to this specification, in the presence of two subscribing witnesses.

JOSEPH ARTHUR HENRY HATT.
